(57) **CLAIM**

The ornamental design for a paper product having a surface pattern, as shown and described.

DESCRIPTION

The sole FIGURE is a top view of a paper product having a surface pattern.

The dash-dot-dot-dash broken lines along the outer boundary of the paper product depict the boundaries of the claimed design and form no part of the claim; the dark broken lines within the boundaries form part of the claimed design.

1 Claim, 1 Drawing Sheet
